CENTRIFUGAL SEPARATOR

Arthur U. Ayres, Chestnut Hill, Pa., and George H. Hill, Westfield, N. J., assignors to The Sharples Corporation, Philadelphia, Pa., a corporation of Delaware

Application October 25, 1939, Serial No. 301,144

14 Claims. (Cl. 233—46)

The present invention pertains to centrifugal separators designed to effect separation of two immiscible liquids from each other and separate discharge of said liquids from the centrifugal rotor under liquid balance.

An object of the invention has been to effect more efficient separation of liquids than has heretofore been possible in machines of this type. As the result of the accomplishment of this object, it is possible, by use of machines constructed in accordance with the features of the invention, to increase the efficiency of the separating operation at a given rate of flow of the mixture of liquids to and through the centrifugal separator, or to increase the rate of flow, and hence the capacity of the machine, without impairing the efficiency of the separating operation.

The efficiency of separation of liquids under the influence of centrifugal force has, in centrifugal separators heretofore available, been impaired by reason of two physical features inherent in the design of centrifugal separators, as follows:

1. Turbulence created in the separating chamber of the centrifugal rotor has the result of re-mixing the subsided heavier constituent with the lighter constituent.

2. There has been a tendency for a part of the stratified heavier constituent in the centrifugal rotor to be drawn inwardly toward the dam over which the lighter constituent is discharged from the main body of the centrifugal rotor. The high velocity of flow of the lighter constituent over the dam causes suction of stratified heavier liquid inwardly, and consequent remixing, in centrifugal separators of conventional design.

An object of the invention has been to avoid the above defects in prior art centrifugal separators.

Further objects of the invention, and the manner in which they have been attained, will be evident from a reading of the following specification in the light of the attached drawings, in which,

Figure 1 is a view partly in section and partly in elevation, illustrating the general structure of a centrifugal machine constructed in accordance with the invention, and

Figure 2 is a detailed sectional view through the upper end of the centrifugal rotor illustrated in Figure 1.

Referring to the drawings by reference characters, the numeral 10 designates the frame of a centrifugal separator which includes a casing 11

for the rotor of the machine. The mixture of liquids under treatment is fed to the rotor 20, which rotates within the casing 11. The feed means may be of conventional character, and include a conduit 12 which is attached to a feed nozzle 14 by means of a removable connection 13. The feed and bearing features of the lower end of the rotor may be of any desired type but I prefer to employ the type illustrated in the patent to W. H. Bath, No. 1,750,154, dated March 11, 1930, for "Centrifugal machine." Such an arrangement involves a spreader disc 15 (or cone). This disc 15 may be secured within the body of the rotor by means of a plurality of posts 16 which space it from the base of the rotor. The base 19 of the rotor is provided with a downwardly extending boss 17, which is supported within conventional drag mechanism 18 of the general type illustrated in the aforementioned patent to Bath.

Both the base 19 and the head 22 of the rotor are secured to its main body by means of screw-threaded connections. The head of the rotor is provided with a reduced neck 23 which passes through an arrangement of covers 24 adapted to receive the liquids discharged from the rotor and direct these liquids away from the rotor. The neck 23 is secured to the drive spindle 25 by any suitable coupling connection, and this drive spindle 25 is in turn connected to a source of power for rotating the rotor (not shown). A plurality of discharge passages 26 and 26' are arranged within the neck of the head of the rotor and are adapted to direct liquids passing from the main body of the rotor into the covers.

In the operation of the machine, a mixture of liquids is injected through a reduced opening in the upper end of the feed nozzle 14 under pressure and impinges against the spreader disc 15, which causes the mixture to flow outwardly against the periphery of the rotor in the form of a thin spray. Such material will gradually fill the rotor, forming an axially extending substantially cylindrical layer within the inner circumference thereof under the influence of centrifugal force. The centrifugal force due to the rotation of the rotor will effect a movement of the heavier liquid through the lighter liquid and against the periphery of the rotor. When the liquids within the rotor reach a sufficient depth to overflow the weir 27, the lighter liquid will be continuously discharged through the inner discharge passages 26' at the same time that the heavier liquid is discharged through the passages 26. A ring dam 28 controls the discharge of

the heavier effluent from the centrifugal rotor, and the relation between the inner circumference of this ring dam 28 and the weir 27 determines the dividing line between liquids subjected to separation within the rotor, after an equilibrium condition has been reached.

The features of the machine described in detail above form no part of my present invention, since they conform to well known principles of design which will be readily understood by those associated with the art of centrifugal separators. Other features of feed and discharge may therefore be substituted for the above features without departing from the spirit of the invention. The novel features of the invention pertain to the provision of an enlarged stratifying chamber adjacent the zone of discharge of the heavier liquid from the main body of the centrifugal rotor. The heavier liquid, after separation from the mixture of liquids passed to the main separating chamber 29 of the rotor, is smoothly passed to a zone of larger diameter before being discharged from the rotor. In order to accomplish this result, the head 22 of the rotor is provided with a plurality of milled openings 30 communicating with the separating chamber 29, and connected by means of drilled holes 31 with an annular zone 32 of substantially larger diameter than the main separating chamber of the rotor. The line of flow of the heavier liquid through the slots 31 is in the same general direction as the line of flow through the main separating chamber of the rotor, since the axes 33 of the holes 31 form an obtuse angle with respect to the rotor axis.

The ring dam 28 is removable and interchangeable with other ring dams of larger or smaller internal diameter, in order to render the machine adjustable to obtain the desired liquid balance conditions with respect to the particular liquids being subjected to centrifugation. These ring dams are preferably so co-related with the inner circumference of the portion 32 of the rotor, the inner circumference of the wear 27, and the relative specific gravities of the liquids to be subjected to centrifugation, as to afford separating conditions such that the dividing line between the liquids being subjected to centrifugation is of greater diameter than the maximum internal diameter of the main separating chamber of the rotor; i. e., the dividing line between the stratified liquids in the rotor lies beyond the inner circumference of the separating chamber 29, and within the drilled holes 31.

The manner in which the objects of the invention have been attained will now be apparent. The mixture of liquids fed to the rotor through the feed nozzle 14 is passed by the spreader disc 15 against the wall of the rotor. The heavier liquid is forced, under the influence of centrifugal force, to pass to the inner circumference of the circumferential wall of the main separating chamber 29 of the rotor. Since the dividing line between stratified liquids is radially beyond the inner circumference of the chamber 29, however, no substantial quantity of the heavier liquid will collect in the chamber 29, and the particles of heavier liquid separated in this chamber will remain at the very periphery 70 of the chamber and flow rapidly upward into the chamber 32. These particles will be retained at the same velocity of rotation as the rotor during passage outwardly to chamber 32, by the milled slots 30 and drilled holes 31, which have 75

the effect of accelerator wings in maintaining the heavier liquid at the speed of rotation of the rotor, thereby avoiding turbulence such as would occur in case an accelerator structure were not

5 provided in this region. The heavier liquid will be collected within the holes 31 and space 32 and discharged under liquid balance against the lighter liquid through the slots 26 and across the ring dam 28. Since the direction of flow 10 of the heavier liquid through the holes 31 is such as to provide no sudden reversal of flow incident to passage of the heavier liquid into the space 32, turbulence and danger of re-mixing of separated constituents will be avoided in this zone. 15 Tendency for the heavier liquid to be discharged across the weir 27 with the lighter liquid is likewise avoided, since no substantial layer of heavier liquid is maintained in the main separating chamber of the rotor 29.

20 In the practice of the invention, it is preferable that a centrifugal rotor having a main separating chamber of substantially cylindrical cross section be employed, since the use of such a rotor is best adapted to the attainment of the 25 object of maintenance of a minimum quantity of the heavier separated effluent in the main separating chamber of the rotor.

It is also preferable that a centrifugal rotor be employed which contains no stratifying discs, 30 or in any case, to avoid feed of liquid through openings located between the inner and outer circumferences of stratifying discs. Feed of liquid through such openings, in a machine having the features of my invention, would involve 35 mixing of the mixture of liquids fed to the rotor with lighter liquid from which the heavier liquid has been substantially completely removed, and would thus, to a large extent, defeat the objects of the invention. A particular advantage of the 40 invention consists in avoidance of re-mixing of liquids after sedimentation of the heavier liquid has once been accomplished, and the use of discs having feed openings would cause such remixing, even adjacent the discharge of liquids from the 45 bowl.

The main body of the head of the rotor is preferably constructed of two or more parts, in order to facilitate cleaning of the rather complicated series of passages 30, 31 and 26 through 50 the head. This is accomplished by providing a surrounding sleeve 34, which is connected by an external screw-threaded arrangement 35 with the outer circumference of the head 22, as illustrated. When the operator wishes to clean the

55 rotor, he first removes the nut 36 by which the ring dam 28 is clamped in place, and he then removes the sleeve 34 from the head 22, and the head 22 from the main body of the rotor. When the machine is disassembled in this manner, the 60 passages 30, 31 and 26 are readily accessible for cleaning.

Modifications will be obvious to those skilled in the art, and I do not therefore wish to be limited except by the scope of the subjoined claims.

65 I claim:

1. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber in which sedimentation of the heavier liquid is adapted to occur under the influence of centrifugal force,

and a chamber of substantially larger diameter than said main separating chamber in the line of flow of liquid from said main separating chamber to the weir over which the heavier effluent flows from the centrifugal rotor, said chamber of larger diameter communicating with the main separating chamber and with the weir for controlling discharge of the heavier effluent from the centrifugal rotor, said chamber of larger diameter being provided with accelerator means to maintain the heavier effluent discharged into said chamber at a uniform velocity of rotation during its passage from the main body of the rotor through said chamber of enlarged diameter, whereby turbulence which would otherwise occur in passage of the liquid from a smaller to a larger diameter is avoided.

2. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber in which sedimentation of the heavier liquid is adapted to occur under the influence of centrifugal force, and a chamber of larger diameter than said main separating chamber adjacent the zone of discharge of the heavier effluent from the centrifugal rotor, said chamber of larger diameter communicating with the main separating chamber and with the weir for controlling discharge of the heavier effluent from the centrifugal rotor, said chamber of larger diameter being provided with accelerator wings to maintain the heavier effluent discharged into said chamber at a uniform velocity of rotation during its passage from the main body of the rotor through said chamber of enlarged diameter, said weirs being so proportioned that in normal operation the diameter of the dividing line between the separated balanced liquids in said centrifugal rotor is greater than the maximum internal diameter of the main separating chamber of the rotor.

3. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber in which sedimentation of the heavier liquid is adapted to occur under the influence of centrifugal force, and a chamber of substantially larger diameter than said main separating chamber in the line of flow of liquid from said main separating chamber to the weir over which the heavier effluent flows from the centrifugal rotor, said chamber of larger diameter communicating with the main separating chamber and with the weir for controlling discharge of the heavier effluent from the centrifugal rotor, said chamber of larger diameter being provided with accelerator wings to maintain the heavier effluent discharged into said portion at a uniform velocity of rotation during its passage from the main body of the rotor through said chamber of enlarged diameter, the entrance to said chamber of larger diameter extending in the same general direction as the line of flow of liquid through the main separating chamber of the rotor, and at an obtuse angle with respect to said line, whereby tur-

bulence which would otherwise occur in passage of the liquid from a smaller to a larger diameter is avoided.

4. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber in which sedimentation of the heavier liquid is adapted to occur under the influence of centrifugal force, and a chamber of larger diameter than said main separating chamber adjacent the zone of discharge of the heavier effluent from the centrifugal rotor, said chamber of larger diameter communicating with the main separating chamber and with the weir for controlling discharge of the heavier effluent from the centrifugal rotor, said weirs being so proportioned that in normal operation the diameter of the dividing line between the separated balanced liquids in said centrifugal rotor is greater than the maximum internal diameter of the main separating chamber of the rotor.

5. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber in which sedimentation of the heavier liquid is adapted to occur under the influence of centrifugal force, and a chamber of larger diameter than said main separating chamber adjacent the zone of discharge of the heavier effluent from the centrifugal rotor, said chamber of larger diameter communicating with the main separating chamber and with the weir for controlling discharge of the heavier effluent from the centrifugal rotor, said weirs being so proportioned that in normal operation the diameter of the dividing line between the separated balanced liquids in said centrifugal rotor is greater than the maximum internal diameter of the main separating chamber of the rotor, and the inner circumference of the chamber of larger diameter extending in the same general direction as the line of flow of liquid through the main separating chamber of the rotor, and at an obtuse angle with respect to said line.

6. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber in which sedimentation of the heavier liquid is adapted to occur under the influence of centrifugal force, and a chamber of substantially larger diameter than said main separating chamber in the line of flow of liquid from said main separating chamber to the weir over which the heavier effluent flows from the centrifugal rotor, said chamber of larger diameter communicating with the main separating chamber and with the weir for controlling discharge of the heavier effluent from the centrifugal rotor, said rotor being provided with accelerator means in the zone of

communication between the main separating chamber and said chamber of larger diameter to maintain the heavier effluent discharged into said chamber of larger diameter at a uniform velocity of rotation as it passes from the main body portion of the rotor to said chamber of enlarged diameter, whereby turbulence which would otherwise occur in passage of the liquid from a smaller to a larger diameter is avoided.

7. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber in which sedimentation of the heavier liquid is adapted to occur under the influence of centrifugal force, and a chamber of substantially larger diameter than said main separating chamber in the line of flow of liquid from said main separating chamber to the weir over which the heavier effluent flows from the centrifugal rotor, said chamber of larger diameter communicating with the main separating chamber and with the weir for controlling discharge of the heavier effluent from the centrifugal rotor, said rotor being provided with accelerator wings in the zone of communication between the main separating chamber and said chamber of larger diameter and in said chamber of larger diameter, to maintain the heavier effluent discharged into said chamber at a uniform velocity of rotation during its passage from the main body of the rotor to and through said chamber of larger diameter, whereby turbulence which would otherwise occur in passage of the liquid from a smaller to a larger diameter is avoided.

8. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber of substantially cylindrical cross section in which sedimentation of the heavier liquid is adapted to occur under the influence of centrifugal force, and a chamber of substantially larger diameter than said main separating chamber in the line of flow of liquid from said main separating chamber to the weir over which the heavier effluent flows from the centrifugal rotor, said chamber of larger diameter communicating with the main separating chamber and with the weir for controlling discharge of the heavier effluent from the centrifugal rotor, said chamber of larger diameter being provided with accelerator wings to maintain the heavier effluent discharged into said portion at a uniform velocity of rotation during its passage from the main body of the rotor through said chamber of enlarged diameter, whereby turbulence which would otherwise occur in passage of the liquid from a smaller to a larger diameter is avoided.

9. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber of sub-

stantially cylindrical cross section in which sedimentation of the heavier liquid is adapted to occur under the influence of centrifugal force, and a chamber of larger diameter than said main separating chamber adjacent the zone of discharge of the heavier effluent from the centrifugal rotor, said chamber of larger diameter communicating with the main separating chamber and with the weir for controlling discharge of the heavier effluent from the centrifugal rotor, said chamber of larger diameter being provided with accelerator wings to maintain the heavier effluent discharged into said chamber of larger diameter at a uniform velocity of rotation during its passage from the main body of the rotor through said chamber of enlarged diameter, said weirs being so proportioned that in normal operation the diameter of the dividing line between the separated balanced liquids in said centrifugal rotor is greater than the maximum internal diameter of the main separating chamber of the rotor.

10. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber of substantially cylindrical cross section in which sedimentation of the heavier liquid is adapted to occur under the influence of centrifugal force, and a chamber of substantially larger diameter than said main separating chamber in the line of flow of liquid from said main separating chamber to the weir over which the heavier effluent flows from the centrifugal rotor, said chamber of larger diameter communicating with the main separating chamber and with the weir for controlling discharge of the heavier effluent from the centrifugal rotor, said chamber of larger diameter being provided with accelerator wings to maintain the heavier effluent discharged into said portion at a uniform velocity of rotation during its passage from the main body of the rotor through said chamber of enlarged diameter, the entrance to said chamber of larger diameter extending in the same general direction as the line of flow of liquid through the main separating chamber of the rotor, and at an obtuse angle with respect to said line, whereby turbulence which would otherwise occur in passage of the liquid from a smaller to a larger diameter is avoided.

11. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber of substantially cylindrical cross section in which sedimentation of the heavier liquid is adapted to occur under the influence of centrifugal force, and a chamber of larger diameter than said main separating chamber adjacent the zone of discharge of the heavier effluent from the centrifugal rotor, said chamber of larger diameter communicating with the main separating chamber and with the weir for controlling discharge of the heavier effluent from the centrifugal rotor, said weirs being so proportioned that in normal operation the diameter of the dividing

line between the separated balanced liquids in said centrifugal rotor is greater than the maximum internal diameter of the main separating chamber of the rotor.

12. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber of substantially cylindrical cross section in which sedimentation of the heavier liquid is adapted to occur under the influence of centrifugal force, and a chamber of larger diameter than said main separating chamber adjacent the zone of discharge of the heavier effluent from the centrifugal rotor, said chamber of larger diameter communicating with the main separating chamber and with the weir for controlling discharge of the heavier effluent from the centrifugal rotor, said weirs being so proportioned that in normal operation the diameter of the dividing line between the separated balanced liquids in said centrifugal rotor is greater than the maximum internal diameter of the main separating chamber of the rotor, said centrifugal rotor being greater than the maximum internal diameter of the main separating chamber of the rotor, and the entrance to said chamber of larger diameter extending in the same general direction as the line of flow of liquid through the main separating chamber of the rotor, and at an obtuse angle with respect to said line.

13. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber of substantially cylindrical cross section in which sedimentation of the heavier liquid is adapted to occur under the influence of centrifugal force, and a chamber of substantially larger diameter than said main separating chamber in the line of flow of liquid from said main separating cham-

ber to the weir over which the heavier effluent flows from the centrifugal rotor, said chamber of larger diameter communicating with the main separating chamber and with the weir for controlling discharge of the heavier effluent from the centrifugal rotor, said rotor being provided with accelerator wings in the zone of communication between the main separating chamber and said chamber of larger diameter to maintain the heavier effluent discharged into said chamber of larger diameter at a uniform velocity of rotation as it passes from the main body portion of the rotor to said chamber of enlarged diameter, whereby turbulence which would otherwise occur in passage of the liquid from a smaller to a larger diameter is avoided.

14. In a centrifugal separator of the liquid balance type, a centrifugal rotor, means for feeding a mixture of liquids to be separated to the centrifugal rotor, separate weirs for controlling separate discharge of said liquids under liquid balance against each other after separation thereof in said centrifugal rotor, said centrifugal rotor comprising a main separating chamber of substantially cylindrical cross section in which sedimentation of the heavier liquid is adapted to occur under the influence of centrifugal force, and a chamber of substantially larger diameter than said main separating chamber in the line of flow of liquid from said main separating chamber to the weir over which the heavier effluent flows from the centrifugal rotor, said chamber of larger diameter communicating with the main separating chamber and with the weir for controlling discharge of the heavier effluent from the centrifugal rotor, said rotor being provided with accelerator wings in the zone of communication between the main separating chamber and said chamber of larger diameter and in said chamber of larger diameter, to maintain the heavier effluent discharged into said chamber of larger diameter at a uniform velocity of rotation during its passage from the main body of the rotor to and through said chamber of larger diameter, whereby turbulence which would otherwise occur in passage of the liquid from a smaller to a larger diameter is avoided.

ARTHUR U. AYRES.
